UNITED STATES PATENT OFFICE.

EDWIN R. TALLEY AND ROBERT P. NORTON, OF ALGONA, IOWA.

TELEPHONE-RECORDER.

1,131,439.

Specification of Letters Patent.

Patented Mar. 9, 1915.

Application filed August 25, 1913. Serial No. 726,496.

To all whom it may concern:

Be it known that we, EDWIN R. TALLEY and ROBERT P. NORTON, citizens of the United States, residing at Algona, in the county of 5 Kossuth and State of Iowa, have invented certain new and useful Improvements in Telephone-Recorders; and we do declare the following to be a full, clear, and exact description of the invention, such as will enable others skilled in the art to which it 10 pertains to make and use the same.

This invention relates to telephony, and more especially to combined telephones and phonographs so-called; and the object of 15 the same is to produce a combined instrument of this kind having manual controls whereby an incoming message may be recorded by the receiver as it is spoken by the sender and repeated later to the receiver, or 20 possibly taken from the instrument and repeated to any one. Much difficulty has been experienced in recording telephone messages in such manner that the sender may not repudiate his statement, and this is the purpose 25 of the present invention. Broadly speaking the idea is carried out by the use of a supplemental receiver, and switch mechanism whereby it is thrown into or onto the telephone circuit so that the incoming message 30 is received in two receivers, said supplemental receiver standing adjacent a phonograph or graphophone mechanism so that the incoming message is recorded thereon.

35 The invention further consists in the details of construction and the mechanism for carrying out the general idea, all as herein-after more fully described and claimed and as shown in the drawings wherein—

40 Figure 1 is a front elevation and Fig. 2 a side elevation of this instrument. Fig. 3 is a vertical section through the casing of the instrument, showing the contained mechanism in elevation. Fig. 4 is an enlarged 45 vertical section, taken substantially on the line 4—4 of Fig. 3. Fig. 5 is an elevation in detail showing the train of gears for connecting the two drums, being taken substantially on the line 5—5 of Fig. 6; and 50 Fig. 6 is an elevation of the shifting mechanism, showing the parts in different position from that illustrated in Fig. 3. Fig. 7 is a

plan view of the motor. Fig. 8 is a sectional detail of the reversing gear.

Our invention includes an ordinary telephone mounted within an amplified casing whose lower portion is designed to contain the improvement or addition thereto; said addition comprising in the present instance a motor such as ordinarily employed in the 55 commercial graphophone or dictaphone, the graphophone mechanism herein shown as having recording and reproducing needles and means for setting them, a winding mechanism for the sensitized material on which 60 the graphophone record is made (in this instance a film), and the means for running this winding mechanism either forward or in reverse direction, which in the present instance are connections between the 65 motor and the winding mechanism as shown. The telephone T may be of any suitable type so long as it is adapted to this improvement, and needs no further description as it is amply illustrated in Fig. 3. The 70 motor M is shown as a spring motor of that class ordinarily employed in graphophones, although we reserve the right to drive this motor electrically or in any other way. It 75 needs no further description, except that we 80 may say that a lever 1 is shown as pivoted at 2 and having an arm 3 depending from its pivot and carrying a brake shoe adapted to be thrown into contact with a disk 5 on the governor 6 which forms a part of this type 85 of graphophone motor; and such contact of the brake or brake shoe 4 is ordinarily made by the weight of the outer end of the lever 1 which projects through an upright slot 1' in the casing, although the lever 90 might be raised and held raised by hand or otherwise to permit the motor to run as described below.

The sensitized material in the present instance is a film F passing over a roller 10 adjacent the graphophone G, then under another roller 11, and its upper end wound on a drum 12 while its lower end is wound on another drum 13—these drums and the gears connecting them constituting the winding 100 mechanism W if a film F be employed. However, we reserve the right to employ a disk record or a cylinder in connection with the graphophone G, so long as the general

idea is maintained. In the present illustration, the power wheel 14 of the motor is belted at 15 to a driven pulley 16 whose shaft has slidably mounted thereon a gear 17 adapted 5 to be thrown directly into mesh with the gear 18 on the uppermost drum 12 to move the same in one direction, and adapted to be moved out of mesh with this gear 18 and into mesh with an idle gear 19 which in 10 turn meshes with another gear 20 on the shaft of the lowermost drum 13 when the film F is to be moved in the other direction; and the means for shifting the gear 17 is typically illustrated herein as a sliding rod 15 15 having a handle 22.

The graphophone G is herein illustrated as comprising a recording needle 23 actuated by a diaphragm 24, and a reproducing needle 25 acting on a diaphragm 26 20 transmitting its message to a horn 27 which leads through the casing to the exterior. However we do not wish to be limited to the type of graphophone employed. In the present embodiment, also, we have shown 25 the recorder as capable of being thrown out of action by a sliding rod 28 having a handle 29 outside of the casing, and the reproducer is also capable of being thrown out of action by means of a sliding rod 30 30 having a handle 31 outside the casing; suitable mechanism may be employed for placing the graphophone under the manual control of the operator receiving the message. It will be seen that the parts thus far de- 35 scribed may be and by preference are mechanisms of the ordinary construction now in general use and which perform their functions as well known in the art. From time to time the motor M is wound by means of 40 its handle, and when the lever 1 is raised this motor runs and through the connections R it drives the film-winding mechanism W in one direction or the other according as the gear shifter is set by its 45 handle 22. As the film F moves over the roller 10, if the recording needle 23 is thrown into action a record is made upon the film; or, such a record having already been made and the film rewound upon the 50 upper drum 12, if the recorder 23 is thrown out of action and the reproducing needle 25 is thrown into action, the record on the film will be reproduced through the horn 27 in a manner which will not be necessary to de- 55 scribe.

Coming now more strictly to what might be called the details of the present invention as associated with the mechanisms above described, the numerals 40 and 41 60 designate the wires of a shunt circuit led from the line wires of the telephone system down through a partition 38 preferably provided within said casing to divide the telephone compartment at the upper por-

tion thereof from the remainder of the in- 65 terior of the casing 39 which contains the recording mechanism. One of the wires, as 40, leads through a snap switch or circuit breaker 43 so that the attachment can be cut out or cut in at the will of the receiving operator, and then this wire as well as the other wire 41 leads to a supplemental telephone receiver 44 suspended below the partition 38 and with its mouth over the dia- 70 phragm 24 of the recorder of the grapho- 75 phone as best seen in Fig. 4.

Another important feature of the invention is the provision of a tape 45 which may be of paper or might in fact be one edge of the film F, so long as it is wound on the 80 drums 12 and 13 alongside and parallel to said film; and in the casing 39 opposite this tape or strip 45 is formed a hole 46 through which an ordinary pencil P may be inserted as seen in dotted lines in Fig. 4. 85

With the assembly of the mechanism above described, either in the precise manner illustrated or in any similar manner which will bring about the end desired, and the addition of the supplemental receiver 90 and the circuit connecting it with the telephone circuit, and the indicating mechanism comprising the tape and the pencil; the operation of this device is as follows: Let us assume that a call comes over the 95 wires from some one who is going to make the user an important communication, such as an offer or the like, which it is important to have recorded for use in case of a subsequent withdrawal. The user unhooks the 100 telephone receiver and is informed that this is the message that he is expecting, and immediately he turns the switch 43 and the lever 1. The motor now begins to run and the film F is drawn through the graphophone mechanism G over the roller 10, and the user has to but push in the handle 29 to throw the recording needle 23 onto the film ready to make a record. The speaker now sends his message over the telephone line 110 and it is received in the ear of the user, but at the same time it runs down the shunt circuits 40-41 and through the supplemental receiver 44 so that the diaphragm 24 causes the recording needle 23 to make a record on 115 the film F. Soon the speaker rings off, and both he and the user hang up their telephones; but the record remains on the film, and the receiver may then actuate the shifter by means of the handle 22 to rewind 120 the film—first having raised the recording needle 23—after which he can throw on the reproducing needle 25 and have the message spoken to him through the horn 27. In fact, this section of the film may be run 125 through the graphophone again and again to repeat what offer was made, or if necessary it might be taken from this machine

and carried to another where it could be reproduced in court in case the person making the offer should deny or repudiate it and the offeree sue as a result thereof. It 5 will be obvious that the attachment will have the same functions and possibilities if the sensitized element F were a disk or a cylinder record, although we have illustrated it as a film and described the operation 10 of a film in connection with the mechanism necessary to drive it one way and the other.

The use of the indicating mechanism alongside the film F will now be obvious. If 15 an ordinary pencil P be inserted in the hole 46 with its point against the tape 45, whenever a certain piece of the film F has been wound off of the drum 12 onto the drum 13 a mark will be made on the tape alongside 20 this piece of the film, and it is quite easy for the operator to remove the pencil as he re-winds this section of film, and to ascertain by the beginning of said mark where was the beginning of the message that has just been 25 recorded on the film throughout this stretch of the same. Of course any other suitable device may be substituted for registering or indicating what portion of the film has been employed, but this trivial detail is probably 30 more useful where a film F is utilized instead of a disk or cylinder.

From what has been said and from what is shown in the drawings, it will be obvious that wide modification in details may be 35 adopted without departing from the spirit of our invention, and that much latitude must therefore be allowed to the manufacturers. The proportions and materials of parts are obviously not essential.

40 What is claimed as new is:

1. The combination with a telephone and its casing, a supplemental casing adjacent the first-named casing and separated therefrom by a transverse partition, the wall of 45 said supplemental casing having a hole, a supplemental receiver within the supplemental casing, a shunt circuit connecting the telephone line wires with said receiver and itself consisting of two wires led through 50 said partition, and a snap switch in the shunt circuit and having its handle on the exterior of the casing; of a graphophone mounted within said supplemental casing and having its recording mechanism actuated by 55 said supplemental receiver, a motor for winding and rewinding the sensitized element of the graphophone, a tape on said sensitized element and passing across the hole in the casing for the purpose set forth, 60 and manual controls for all the graphophone mechanisms leading to the exterior of the casing.

2. The combination with a telephone and its casing, a supplemental casing below the

first-named casing and divided therefrom by 65 a transverse partition, the wall of said supplemental casing having an upright slot, a supplemental receiver within the supplemental casing, a shunt circuit connecting the telephone line wires with said receiver and 70 itself consisting of two wires led through a hole in said partition, and a snap switch in one of said wires of the shunt circuit and having its handle on the exterior of the casing; of a graphophone mounted within 75 said supplemental casing and having its recording mechanism actuated by said supplemental receiver, a motor for winding and rewinding the sensitized element of the graphophone, a brake for the motor, a brake-lever extending through said slot and normally holding the brake applied, and manual controls for the graphophone mechanisms leading to handles outside of the supplemental casing. 85

3. The combination with a telephone and its casing, a supplemental casing whose wall has an upright slot and a hole, a supplemental receiver within the supplemental casing, a shunt circuit connecting the telephone line wires with said receiver, and a switch in the shunt circuit and having its handle on the exterior of the casing; of a graphophone mounted within said supplemental casing and having its recording 95 mechanism actuated by said supplemental receiver, a motor for winding and rewinding the sensitized element of the graphophone, a brake for the motor whose lever extends through said slot, and a tape parallel 100 said sensitized element and passing across the hole in the casing, for the purpose set forth. 100

4. The combination with a telephone including a casing, a supplemental receiver 105 therein, a shunt circuit connecting the line wires of the telephone with said receiver, and a switch in said circuit; of a graphophone also mounted in said casing and having its recording mechanism actuated by 110 said supplemental receiver, a motor also arranged in the casing for winding and rewinding the sensitized elements of the graphophone, a governor for said motor including a brake disk, an angular lever fulcrumed at the junction of its arms within 115 the casing and having one arm thereof disposed loosely through the front wall of said casing, the last mentioned wall of said casing being provided with a slot through 120 which said arm is disposed, and a brake shoe carried on the end of the other arm of said lever adapted for normal engagement with the brake disk whereby to prevent the operation of said motor until said lever is raised 125 on its fulcrum point.

5. In a device of the character described, a recorder having a needle, a smooth flexible

sensitized band, means whereby said band may be fed past said needle, and a comparatively rough tape formed on one edge of said band, whereby the beginning and end 5 of a conversation may be manually inscribed and recorded upon said tape.

In testimony whereof we have hereunto

set our hands in presence of two subscribing witnesses.
